UNITED STATES PATENT OFFICE.

JACOB A. SHUPING, OF MORGANTON, NORTH CAROLINA.

GRATE.

1,143,235.

Specification of Letters Patent. Patented June 15, 1915.

Application filed February 12, 1915. Serial No. 7,815.

To all whom it may concern:

Be it known that I, JACOB A. SHUPING, citizen of the United States, residing at Morganton, in the county of Burke and State 5 of North Carolina, have invented certain new and useful Improvements in Grates, of which the following is a specification.

This invention relates to grates, and more particularly to a grate of improved construction which is especially adapted for use in open fire places, and which comprises alternating bars which are adapted to be rocked for agitating the coals placed upon the grate.

15 An object of the invention is to provide a grate of this character which is simple in construction, and which is efficient in its operation.

Another object is to provide a grate comprising a stationary frame and a rocker frame, and to provide improved means for connecting the rocker frame with the stationary frame.

With these and other objects in view, the 25 invention consists in the novel features of construction, combination and arrangement of parts, as will be hereinafter more fully described, illustrated in the accompanying drawings and claimed.

30 In the drawings, Figure 1 is a top plan view; Fig. 2 is a section on the line 2—2 of Fig. 1, showing in dotted lines the raised position of the rocker frame; Fig. 3 is a detail perspective view of a portion of the 35 lower rear connecting bar; Fig. 4 is a detail view showing the manner of detachably locking the rod within the upper front connecting bar.

Referring to the drawings by numerals, 40 1 designates the stationary frame, while 2 designates the rocker frame. The stationary frame is of the ordinary construction and comprises end grate members 3 which are connected by the usual upper front bar 45 4 and lower rear bar 5, hooks 6 being formed on the upper inner ends of the grate members 3 for engagement with pins or projections in the fireplace to fix the frame 2.

Grate bars 7 connect the bar 5 with the 50 bar 4. These bars are arranged in relatively wide spaced relation, and between each of these bars 7 and cut within the upper face of the bar 5 are recesses 8.

The upper front bar 4 has a substantially 55 U-shaped channel 9 formed in the upper face thereof and this bar, adjacent either end

thereof, has lugs 10 formed on the upper face thereof and projecting within the channel 9.

The rocker frame 2 comprises grate bars 60 11 which are formed on a rod 12 and which are adapted to have their free ends rest in the alternating recesses 8 of the bar 5. The rod 12 is of a size to be snugly received within the channel 9 and has cut-out portions 65 13 formed adjacent either end thereof and which are disposed in alinement with the lugs 10. When the bars 11 are in their normal position resting upon the bar 5, the cut-out portion 13 is then disposed upon the 70 upper face of the rod 12, with the lugs 10 in engagement with the face of the rod 12 in order to lock the same within the channel 9.

When it is desired to remove the rocker frame from the stationary frame, the free 75 ends of the bar 11 are swung to a position as shown in dotted lines in Fig. 4 of the drawings. In this position, the cut-out portions 13 are disposed in releasing alinement with the lugs 10 so that by raising the rocker 80 frame vertically, the rod 12 will be disengaged from the channel 9.

An operating lever 14 is secured to one end of the rod 12 and is adapted to be actuated to rock the rocker frame from a position as shown in full lines in Fig. 2 to a 85 position as shown in dotted lines in the said figure.

From the disclosure of the invention as set forth, it will be noted that a grate has 90 been provided which is readily and easily disassembled or assembled, and one which is thoroughly reliable and efficient in its operation.

From the foregoing description taken in 95 connection with the accompanying drawings, it is thought that the construction and operation of the device will be clearly understood, and while I have herein shown and described one specific form of my invention, 100 I do not wish to be limited thereto, except for such limitations as the claim may import.

What is claimed is:

A grate comprising a stationary frame 105 having a substantially U-shaped upper bar structure, members depending from the rear ends of said bar structure, a lower rear bar supported by said members, stationary grate bars connected with the intermediate portion of said upper bar structure and said 110 lower rear bar, said lower rear bar provided

with alternating recesses, the intermediate portion of said upper bar structure provided with a longitudinal channel extending approximately the entire length thereof, lugs 5 on said upper bar structure overhanging said channel, said upper bar structure provided with a series of cut-outs, said cut-outs communicating with said channel, a rod arranged in said channel and projecting beyond the ends thereof, an operating element 10 on said rod, said rod provided with cut-outs

in alignment with said lugs, a series of grate bars fixed to said rod and operating in said recesses and said first mentioned cut-outs for the purpose specified. 15

In testimony whereof I affix my signature in presence of two witnesses.

JACOB A. SHUPING.
